Patented Feb. 22, 1966

203,835

COMMODE TABLE COMBINATION

Bert J. Klein and Andre Bus, Altavista, and John B. Thorn, Lynchburg, Va., assignors to The Lane Company, Inc., Altavista, Va., a corporation of Virginia

Filed Apr. 19, 1965, Ser. No. 84,869

Term of patent 14 years

(Cl. D33—6)

Fig. 2.

Fig. 3.

The side not shown is like the side shown while the back of the article is plain and unornamented.

We claim:

The ornamental design for a commode table combination as shown and described.
